Inventor,

William Wirt Branch Jr.
Geo. F. Barker, Atty.

UNITED STATES PATENT OFFICE.

WILLIAM W. BRANCH, JR., OF MADISON, OHIO.

FIRE-KINDLER.

SPECIFICATION forming part of Letters Patent No. 281,754, dated August 31, 1880.

Application filed July 22, 1880. (No model.)

To all whom it may concern:

Be it known that I, WILLIAM WIRT BRANCH, Jr., a citizen of the United States of America, residing at Madison, in the county of Lake 5 and State of Ohio, have invented certain new and useful Improvements in Fire-Kindlers; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 My invention relates to improvements in fire-kindlers, as will be hereinafter set forth.

In the drawings, Figure 1 is a perspective view of the fire-kindler complete and ready for use; Fig. 2, a perspective of same unrolled. 20 Figs. 3, 4, 5, and 6 show modifications of my invention.

A represents a small block or stick of wood or other combustible substance or material. B is a thin shaving or sliver of wood cut latitudinally with the grain of timber, one edge of which is cut very thin or to a feather for facility or use in lighting, the other end being of suitable thickness to give it strength and solidity for wrapping about stick A and continue burning a sufficient time to completely 25 kindle and start a fire. The stick A is laid upon one end of the strip or shaving B, as shown in Fig. 2, and forms the support or nucleus about which is wound or wrapped the 30 shaving B, and when wound fastened by a tack or brad, a, Fig. 1. Said kindler may be constructed by winding the shaving or strip B about one or more center pieces or sticks, A, and with thin pieces of wood b, Fig. 6, between the layers, separating and forming air-spaces between them for drafts of air, thus aiding the combustion of the entire kindler; or holes may be made through body of the kindler for the same purpose.

The kindler may be made with or without 45 the block A, or by using a shaving with both edges cut thin or feathered, as shown in Fig. 5, the strip being thickest through the middle; or by lapping the thick edges of two shavings or slivers, as shown in Fig. 4, and wrapping 50 around the block; or by wrapping the block with two shavings the thick ends of which are placed together. It may also be made by piling short pieces of the shavings or slivers with their thick edges one upon another until of 55 suitable size for the purpose intended. In order to more complete ignition and combustion, said kindler may be coated in or saturated with melted resin or other substance quickly ignitable.

Having thus described my invention, what I claim as new, and desire to secure by Letters Patent, is—

1. A fire-kindler composed of a stick or blocks of wood or other combustible material, 65 A, forming a center about which is wrapped a strip or shavings, B, with thin or feathered edges, with or without the thin pieces b between the layers, in the manner and for the purpose described.

2. A fire-kindler composed of a series of shavings or slivers, B, placed with their thick edges one upon another until of suitable size, as and for the purpose set forth.

3. The combination, in a fire-kindler, of a center stick or sticks of wood or other combustible material, A, with shavings or strips B, cut latitudinally with grain of timber and having thin or feathered edges, and thin pieces of wood b, placed at intervals between the shavings or layers, substantially as and for the purpose set forth.

In testimony whereof I affix my signature in presence of two witnesses.

WILLIAM WIRT BRANCH, JR.
